CIGARETTE SUPPORT

Gilbert T. Gorman, New York, N. Y.

Application April 7, 1934, Serial No. 719,479

2 Claims. (Cl. 131—51)

This invention relates to means for holding a cigarette or the like upon a finger, and has for an object to provide means which may be associated with the finger, and simultaneously with the cigarette, whereby the cigarette does not come in contact with the skin, nor is it liable to be lost or thrown away.

A further object of the invention is to provide a device which will hold the cigarette in approximately upright position with the burning end uppermost, and thereby prevent the lighted end from coming in contact with combustible material.

A further object of the invention is to provide a device including a ring, or a segment of a ring, which will maintain itself upon a finger with a ring loop, or other holding device, connected therewith, which will clasp or hold a cigarette relative to the ring.

The invention, therefore, comprises any type of ring or finger encircling or embracing member, whether a complete circle or otherwise, with any form of cigarette holding arrangement secured or attached to, or carried by the ring member, holding the cigarette in a position transversely of the finger.

In the drawing.

Figure 1 is a view in perspective of one type of cigarette support.

Figure 2 is a view in side elevation of the same type, as shown at Figure 1, showing the position when the cigarette is erected, to maintain the lighted end uppermost.

Figure 3 is a perspective view of a different type of cigarette support.

Figures 4 and 5 are views in side elevation of rings with different types of cigarette supports thereon.

Figures 6 and 7 are views in edge elevation of rings with still different modifications of the cigarette supports.

Like characters of reference indicate corresponding parts throughout the several views.

In the type of cigarette support shown at Figures 1 and 2, a band 10 is shown as a segment of a ring. As shown, it is a major segment, but the segment may be any segment found desirable. Upon this ring 10, a loop or sleeve 11 is secured, of such shape and size as to properly contain and hold a cigarette, shown at 12.

While the smoking article shown at Figures 1 and 2 is obviously intended to represent an article commonly known as a cigarette, it is obvious that the device may be used to hold smoking articles in rolled form of any size, shape, or known by any name, whether cigars or otherwise.

and the term "cigarette" is employed merely for convenience, and is intended to cover all such types of smoking articles. The manner of attaching the sleeve 11 arranged to hold the cigarette, as above defined, to the ring or segment 10, is relatively unimportant, but is here shown as formed integral by means of a twist 13. This type would find its best impression in being made from sheet metal, but, of course, the invention is not limited to such material.

At Figure 3, the ring 14 is provided with a shield 15, which underlies the ring 16, which holds the cigarette 12. This is to further prevent the staining or burning of the fingers. At Figure 4, the ring 17 is shown as provided with a spring clasp 18, the ends 19 of which, when compressed, will enlarge the loop of the clamp 18, so that the cigarette 12 may be easily inserted therein, and when released will firmly clamp the cigarette in position.

At Figure 5, the ring 20 is provided with a plate 21 which serves as a shield similar to the shield 15, but is intended to be of less area. This type is provided with spring clasps 22, which hold the cigarette 12 clamped therebetween.

At Figure 6, a ring of conventional type is shown at 23 having a sleeve 24. While this sleeve 24 is shown as indicated, composed of coiled wire, it is to be understood that this is merely a convenient mode of manufacture, and is no limitation upon the invention; a sleeve of such type as to hold a cigarette 12, and of any construction, being within the same scope.

At Figure 7, the ring 25 is indicated as having a bore therethrough to receive a cigarette holder 26 of conventional type. In any case, however, a finger or embracing part is employed with means carried thereby for holding a cigarette either in such position that the cigarette itself may be inserted into the mouth of the user, or by use of the cigarette holder 26, as shown at Figure 7.

I claim:—

1. A cigarette support comprising a finger engaging part, a finger shield carried thereby, and resilient members extending thereabove initially diverging but convergingly curved and terminating in spaced extremities.

2. A cigarette support comprising a finger engaging part, a finger shield carried thereby, a post extending radially therefrom, and resilient members extending thereabove initially diverging but convergingly curved and terminating in spaced extremities.
